Attorneys.

UNITED STATES PATENT OFFICE.

WILL M. KINNARD, OF DAYTON, OHIO, ASSIGNOR TO THE CARTER-CRUME COMPANY, OF NIAGARA FALLS, NEW YORK.

COVER FOR MEMORANDUM-SALES-SLIP BOOKS.

SPECIFICATION forming part of Letters Patent No. 526,397, dated September 25, 1894.

Application filed July 20, 1893. Serial No. 481,014. (No model.)

To all whom it may concern:

Be it known that I, WILL M. KINNARD, a citizen of the United States, residing at Dayton, in the county of Montgomery and State 5 of Ohio, have invented certain new and useful Improvements in Covers for Memorandum-Sales-Slip Books, of which the following is a full, clear, and exact description, reference being had to the accompanying drawings, forming part of this specification.

The object of my invention is to provide a cover for the sales slips within which packages of slips, either loose or bound, may be readily secured, and consists mainly in providing a pair of spring clamps arranged so that they may be readily operated simultaneously to release the old book or insert a new one; the novel features of which will be hereinafter more particularly pointed out and 20 claimed.

In the drawings, Figure 1 is a perspective view of the cover for holding the packages of slips. Fig. 2 is a rear view in cross section taken just within the back wall of the clamp 25 support. Fig. 3 is a similar view showing the clamps raised ready for the insertion of the slips.

A, is a plate of any suitable material, which forms a back or support for the sales slip 30 book. Secured at one end of this plate A, or formed integral therewith, is a receptacle or case B, made up of back wall a, top b, sides or ends c, and a front wall d. This front wall d, extends downward only about half way, 35 so that the lower portion of the receptacle B is open to allow the package of sales slips to be inserted therein back against the rear wall, a, of the receptacle.

C, C, are a pair of levers or clamps pivoted 40 within the receptacle B on the pins e, e, pivoted practically in the same horizontal and vertical planes, and having their inner ends approaching each other. Recesses are formed in these clamps C, C, around the pivotal 45 points e, e, to receive the coiled springs f, f, one end of which bears against the clamp and the other against the bottom A of the receptacle, the springs being preferably coiled around the pins e, e, so that their action keeps 50 the outer ends of the clamps pressed downward. An opening g of suitable size for the

butt end of a lead pencil or writing instrument, is formed in the top b of the receptacle. The outer ends of these clamps are provided with sharpened points h, h, extending downward. A flange or overhanging lip k, is formed at the other or lower end of the plate A, as shown in Fig. 1.

For convenience in use, the case for the slips is then covered with or placed within a suitable card board back cover, and suitably secured thereto; the staples l, l, being employed to secure the receptacle portion to this book cover and the balance of the cover being glued thereto.

When the memorandum sales slip book is to be placed in its cover, the operator passes his pencil D, as shown in Fig. 3, through the opening g, depressing the inner ends and raising the outer ends of the clamps up level 65 with the lower edge of the front wall d. The package of slips is then inserted within the receptacle and the springs f, f, force the points h, h, on the ends of the clamps into the paper slips. To hold the back from displacement, the book of slips is bent up slightly and the lower end slipped under the flange k. The points h, h, pressing against the paper, allow the operator to tear out one slip at a time in the usual way, without displacing the 70 others. In this way using his pencil to depress the clamps both at the same time, the user can readily and quickly insert the package of sales slips in the cover.

Having thus described my invention, what 75 I claim, and desire to secure by Letters Patent, is—

1. In a memorandum sales slip cover, the combination with the cover, of a pair of spring actuated clamps pivoted thereto with their 80 inner ends approaching each other so that they may be depressed at one operation, substantially as shown and described.

2. In a memorandum sales slip cover, the combination of a receptacle open at its lower 85 end, a pair of spring actuated clamps pivoted in the upper portion thereof, so that when depressed they will clear the opening, said clamps having their inner ends approaching each other, and the top having a pencil opening 90 therein over the inner ends of said clamps whereby they may be depressed simultane- 100

ously in one operation, substantially as shown and described.

3. In a memorandum sales slip cover, the combination, of a pair of spring actuated clamps with their inner ends approaching each other pivoted to the cover at one end to hold the upper end of the package of slips and a flange on said cover at the other end

under which the folds of said slips are inserted to hold same from displacement while the written slips are being withdrawn, substantially as shown and described.

WILL M. KINNARD.
